UNITED STATES PATENT OFFICE.

GEORGE W. LALLY, OF BOSTON, MASSACHUSETTS, ASSIGNOR TO LALLY COMMERCIAL BODY COMPANY, OF BOSTON, MASSACHUSETTS, A CORPORATION OF MASSACHUSETTS.

ELEVATING AND DUMPING BODY.

1,158,812.

Specification of Letters Patent. Patented Nov. 2, 1915.

Application filed September 20, 1912. Serial No. 721,397.

To all whom it may concern:

Be it known that I, GEORGE W. LALLY, a citizen of the United States, and resident of Boston, county of Suffolk, and State of Massachusetts, have invented an Improvement in Elevating and Dumping Bodies, of which the following description, in connection with the accompanying drawings, is a specification, like letters on the drawings representing like parts.

My present invention relates to vehicle bodies especially designed for carrying material in lump or granular form, such as coal, broken stone, and the like and, while not limited thereto, is well adapted for use as a part of automobile truck constructions.

The invention has to do especially with improved mechanism for elevating the body from the vehicle frame-work or chassis, and 20 tilting the same to dump its contents, more particularly, by tilting the forward part of the body upward about an axis underneath its rear portion.

The invention provides improved means 25 for starting the lift of the body from its horizontal position so as to enable the initial movement, which is usually the most difficult, to be readily accomplished without undue effort and with no severe strain upon the 30 parts of the apparatus.

The invention further provides improved means whereby the impulse which imparts the tilting movement may, if desired, at the same time raise the rear portion of the body, 35 such elevation of the rear body portion being optional and conveniently under the control of the operator.

Heretofore the lifting or tilting mechanism of this type of vehicle has required a 40 more or less complex arrangement of rods, levers, etc., and has also employed rods or levers of such length that it was impractical to operate them at the initiation of the lifting and tilting movement, between the top 45 sills of the vehicle and the bottom of the vehicle body. Therefore heavy iron braces or brackets were usually secured to the vehicle body, depending below the top of the sills, or braces, iron strips or the like have 50 been applied to the body in order to afford a point of connection for the lifting rods, substantially at the upper or top portion of the body. Such prior constructions were unsatisfactory, requiring an expensive construction, and also a long lifting movement 55

and usually necessitated the initial lifting action to be exerted while the lever or rod therefor was in a position less efficient for such lifting.

To obviate the difficulties both in construction and operation just noted, my invention comprises means to exert the entire lifting impulse directly between the top of the vehicle sills and the bottom of the vehicle body, and furthermore employs comparatively 60 short lifting rods or levers, thus securing a light and economical structure and one permitting great ease and speed in operation.

Still further features of my present invention are to provide mechanism which will 70 automatically and simultaneously act to raise or tilt the forepart of the vehicle body, while moving the entire vehicle body rearwardly, and further allowing it to rest in its firm and solid supporting bearings on the rear 75 sill of the frame. This feature is of special importance in the large modern automobile freight trucks, where a specially heavy load is handled as it would be entirely impractical, if not impossible, to actually lift both 80 ends of the vehicle body upwardly in order to secure a tilting movement.

The invention will be better understood from the following detailed description, taken in connection with the accompanying 85 drawings, and will be thereafter pointed out in the appended claims.

Referring to the drawings, Figure 1 is a plan view of the operative parts of the mechanism, wherein my improvements are embodied, certain parts being broken away and in section; and Fig. 2 is a side elevation of the apparatus.

A vehicle framework, which may be the chassis frame of an automobile truck, is 95 shown at 10 having a usual series of spaced apart, transverse sills 11 fitted thereon, these sills being, as shown, of some little width so as to sustain the body 1 at a spaced elevation above the top of the chassis frame proper 100 10. At the rear end of the body instead of a sill 11, bearing blocks 12 are mounted on the chassis frame, providing bearings for a shaft 13 on which are fitted roller supports 14 to be engaged by wedge formations 105 15, fixed to the rear end of the body, and the function whereof is later more particularly explained. Power impulse for the tilting of the body is derived primarily as shown from a crank shaft 16, connected by 110

- reducing gearing 17 to a shaft 18, these parts being suitably journaled in bearing blocks or plates 19 upstanding from the chassis frame. The shaft 18 has fixed thereon winding drums 20 for winding up chains, or the like 21, which are fixed, as at 22 to a shaft 23, having at its ends flanged rollers 24 adapted to rest on and move along trackways formed thereon on the chassis frame.
- 10 As shown, the portion of these trackways toward the forward part of the body are horizontal, as seen at 25, and the rearward part thereof is formed by wedge members providing upwardly inclined track portions 26, this arrangement being preferable for most effective action, as later explained. The shaft 23 is engaged by long lifting link bars 27, pivoted at their rear ends to the body as seen at 28, at points relatively remote from the front of the body and the forward ends of these bars are provided with closed, elongated slots 29, in which the shaft 23 has bearings and through the length of which it is adapted to move. Another and shorter pair of lifting link bars 30 are pivoted to the body at 31, some little distance forward of the pivot points 28, and these bars have at their lower forward ends forked or hook formations 32, adapted to engage over the shaft 23 when the body is in lowered position. One of the forks 33 at the forward or outer side of these bars is elongated, as shown, so as to remain in contact with the shaft 23 as the body is elevated to guide these bars down for the forked formations 32 to engage the shaft 23 again, when the body is lowered. It will be understood that, by reason of the bars 30 being shorter than the bars 27 and pivoted nearer the front of the body, they extend down therefrom to the shaft 23 at a considerably greater angle than the relatively longer bars 27, which are pivoted to the body farther back thereon. For this reason, when the crank shaft 16 is operated to cause the chains 21 to draw the shaft 23 backward, the first action is for this shaft to exert force rearwardly and upwardly on the bars 30, and by reason of these bars extending upwardly at a considerable angle, a relatively large component of this force is exerted in lifting the body, the effectiveness of the lifting action being also correspondingly greater by reason of the pivot points 55 of the bars 30 being relatively near the front of the body and farther from its axis 18 of the pivotal movement. The start of tilting movement from the horizontal is further made easier by the fact that the 60 rollers 24 begin their movement along the horizontal track portions 25 and do not reach the inclines 26 until the tilting movement has been well started. During this initial movement the bars 27 are moving relatively to the shaft 23, so that this shaft

travels through the length of the elongated slots 29. By the time the shaft has reached the end of these slots, the body has been tilted to a considerable degree, so that the long bars 27 now extend upward at a considerable angle, and are adapted to take up the further tilting of the body without requiring undue effort on the part of the operator, or without producing an excessive rearward thrust on the body. About this time the rollers 24 start on the inclined track portions 26, so that the subsequent and final stages of the tilting movement are quickly effected and the body brought to the desired angle for dumping its contents in the shortest possible time, and with the least possible effort.

It may sometimes be desirable to elevate the rear of the body, and my invention further provides means whereby this may be accomplished at will by the same power impulse which tilts the body for dumping. When it is desired to merely swing the body about the axis shaft 13 without lifting its rear end, hooks 34 pivoted at 35 to the rear of the body are adapted to swing down over and engage the shaft 13, as seen in Fig. 2, thus preventing any rearward movement of the body. When, however, it is desired that the rear of the body shall be elevated, these hooks are swung upward away from the shaft 13, and the body is then permitted a limited, rearward movement, whereby the wedge portions 15 ride along up on the rollers 14, causing the rear of the body to be elevated, as it moves backward. The body is prevented from moving backward too far along the wedges 15 by other hooks 36 pivoted at 37, so as to engage the shaft 13 before the rollers 14 pass off the wedges 15.

The simplicity of construction of my improved vehicle and the ease of operation, as well as the possibility of speed in tilting the vehicle body will be readily appreciated. By means of the short thrusting member 110 30, which acts upon the forward end of vehicle body and exerts the initial thrusting movement while the rolls 23 are being moved along the straight and level portion 25 of the sills, I am enabled to handle a very 115 heavy load with as much speed and ease as formerly was required to lift and tilt comparatively small loads. The bearing of the rolls 23 directly upon the top of the wagon sills provide a very firm and secure support 120 and permits the entire lifting mechanism to be made with a minimum weight of material and brings the load on the vehicle frame where it can be best sustained.

There is thus constituted a mechanism of 125 maximum simplicity and great strength of construction, adapted to apply the power at the beginning of the tilting lift of the body in an effective manner, so that the beginning of the lift is accomplished as easily as the 130

subsequent stages. The improved construction further permits the back of the body to be raised or not as desired by merely swinging the hooks 34 so as to have them engage the shaft 13 or not at will.

It will be understood that various of the constructional details shown in the illustrative embodiment of the invention herein set forth may be modified without departing 10 from the substance of the invention in its broader aspects, and I therefore do not desire to be limited to the particular disclosure herein, or in any way, except as set forth in the appended claims.

Having described my invention, what I claim as new and desire to secure by Letters Patent is:

1. An elevating and dumping vehicle, having a vehicle frame and a movable body 20 adapted to be tilted about a pivot adjacent the rear end thereof, mechanism to tilt said body about said pivot, actuated by a longitudinally movable member, adapted to actuate two pairs of thrust members successively during its continuous longitudinal movement, one pair of thrust members being comparatively short to secure a relatively direct upward tilting thrust on said body to initiate the tilting movement and being detachable from said longitudinal movable member, and the second thrust element being constructed and arranged to take up and continue the tilting action at a point on said body nearer the pivot than the point on said body engaged by the first thrust members.

2. An elevating and dumping vehicle, having a vehicle frame and a movable body adapted to be tilted about a pivot adjacent the rear end thereof, mechanism to tilt said 40 body about said pivot, actuated by a longitudinally movable member adapted to bear on top of the vehicle frame during the first portion of its movement, and adapted to actuate two thrust elements successively during its continuous longitudinal movement,

one thrust element being comparatively short to secure a relatively direct upward tilting thrust on said body to initiate the tilting movement only and then being inoperative to cause further tilting and the 50 second thrust element being constructed and arranged to take up and continue the tilting action at a point on said body nearer the pivot than the point on said body engaged by the first thrust element, both said 55 thrust members having direct pivoted connection with the body portion of the vehicle at the points of thrust thereon.

3. An elevating and dumping vehicle, having a vehicle frame and a movable body 60 adapted to be tilted on said frame about its rear end, mechanism to tilt the body, comprising means acting between the top of the vehicle frame and the bottom supports of said body, said means including two pairs of 65 thrust members each independently pivoted to the body and actuated from a single horizontal shaft having provision to roll upon the top of the frame during the initiation of the tilting action and then to roll upwardly 70 on an incline during the completion of the tilting action, means to move said horizontal shaft longitudinally, one pair of relatively short thrust members being actuated to initiate the tilting thrust while said horizontally 75 movable bar is rolled on the straight frame, and the other pair of thrust members being actuated to complete the tilting action only during the movement of said horizontal bar on its incline, the pair of 80 short thrust members being operatively disconnected from the horizontal shaft during the completion of the tilting action.

In testimony whereof, I have signed my name to this specification, in the presence 85 of two subscribing witnesses.

GEORGE W. LALLY.
